(57) **CLAIM**

We claim the ornamental design for a watch, as shown and described.

DESCRIPTION

FIG. 1 is a perspective view of a watch in an open configuration, showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a perspective view thereof in a closed configuration.

The broken lines in the drawings show portions of the watch that form no part of the claimed design. FIGS. 1 and 8 show the watch at a larger scale.
